UNITED STATES PATENT OFFICE.

JOHN CAREY, OF VICTORIA, MISSOURI.

IMPROVED SPRING FAN ATTACHMENT.

Specification forming part of Letters Patent No. **92,513**, dated July 13, 1869.

To all whom it may concern:

Be it known that I, JOHN CAREY, of Victoria, in the county of Jefferson and State of Missouri, have invented a new and Improved Spring Fan Attachment; and I do hereby declare that the following is a full, clear, and exact description thereof, which will enable others skilled in the art to make and use the same, reference being had to the accompanying drawing, forming part of this specification.

This invention relates to improvements in spring-propelling fan attachments for chairs, beds, and other places, the object of which is to provide an improved attaching apparatus, adapted to support the fan in any required position for directing the blast; also, an improved arrangement of propelling-springs, calculated to give a more steady and uniform motion, and to continue the motion a greater length of time.

The drawing represents a side elevation of my improved apparatus.

A represents a bent rod of wire adapted for the support of the journal of the rotary fan B, and for the frame C of the spring-propelling mechanism, and also for the connection of an adjustable clamping-bracket, D, for fastening the apparatus in any desired position to a bed, chair, or other fixture. The fan-shaft is supported at its outer end in the end E of the said rod, which is bent around to a parallel position vertically with the main part of the

said stock, but sufficiently below it horizontally to permit the said shaft to be suspended under the said stock at F. The other end of the said fan-shaft is supported in the frame C of the propelling mechanism. The frame C of the propelling mechanism is connected to the stock, by screws, at G.

The clamp consists of a bar, D, connected to the stock by arms G, in which the stock may turn and be secured by a set-screw and an adjustable clamp, H, capable of sliding up or down on the said bar, and also provided with a set-screw. This clamping device admits of securing the fan attachment in any required position.

For imparting a more uniform motion to the fan, I have attached to the ordinary spring-propelling wheel I another large propelling-wheel and spring, K, which, working in conjunction with the first, will continue the motion after the first has become uncoiled and its power expended.

Having thus described my invention, what I claim as new, and desire to secure by Letters Patent, is—

The combination of the fan B with the duplicate propelling or clock mechanism, the stock A, &c., and clamp D, arranged substantially as specified.

JOHN CAREY.
